UNITED STATES PATENT OFFICE

HARRY C. RICHARDSON, OF NORTH SALEM, NEW YORK, ASSIGNOR TO WARREN TELE-
CHRON COMPANY, A CORPORATION OF MAINE

DESIGN FOR A CLOCK CASE

Application filed October 10, 1930. Serial No. 37,210. Term of patent 14 years.

To all whom it may concern:

Be it known that I, HARRY C. RICHARDSON, a citizen of the United States, residing at North Salem, in the county of Westchester, State of New York, have invented a new, original, and ornamental Design for a Clock Case, of which the following is a specification, reference being had to the accompanying drawings, forming a part thereof. Fig. 1 of

the drawings is a front perspective view of a clock case showing my new design and Fig. 2 shows a side view thereof on a reduced scale.

I claim:

The ornamental design for a clock case as shown.

In witness whereof I have hereunto set my hand this 26 day of Sept., 1930.

HARRY C. RICHARDSON.
